Des. 241,546
Patented Sept. 21, 1976

241,546

HAND HELD SHOWERHEAD

Leandro P. Rizzuto, Brooklyn, N.Y., assignor to
Conair Corporation

Filed Mar. 22, 1976, Ser. No. 669,194

Term of patent 14 years

Int. Cl. D23—01

U.S. Cl. D23—35

Fig. 1.

Fig. 2.

Fig. 3.

Fig. 4.

Fig. 5.

Fig. 6.

Fig. 7.

FIG. 1 is a front perspective view of a hand held showerhead showing my new design;

FIG. 2 is a rear perspective view thereof;

FIG. 3 is a front elevational view;

FIG. 4 is a right side elevational view, the left side being a mirror image of the right side shown;

FIG. 5 is a rear elevational view;

FIG. 6 is a top plan view; and

FIG. 7 is a bottom plan view.

I claim:

The ornamental design for a hand held showerhead, substantially as shown.
